UNITED STATES PATENT OFFICE.

FLOYD D. JONES, OF CLEVELAND, OHIO.

MAGAZINE AND BOOK SUPPORT.

Application filed August 14, 1925. Serial No. 50,210.

The present invention relates to a table attachment for chairs, which embodies novel features of construction whereby it can be readily used in connection with any chair and will provide a very convenient rest for supporting magazines, books or the like in front of the occupant of the chair.

Further objects of the invention are to provide a device of this character which is comparatively simple and inexpensive in its construction, which can be readily placed in position upon the chair, which can be readily adjusted to fit different chairs and support the table in different positions, and which can be folded into a small amount of space when not in use.

For a full understanding of the invention reference is to be had to the following description and accompanying drawings, in 20 which,

Figure 1 is a perspective view of a table attachment for chairs which is constructed in accordance with the invention.

Figure 2 is a top plan view thereof, the 25 seat of the chair being indicated by dotted lines.

Figure 3 is a side elevation with the chair seat indicated in dotted lines, and

Figure 4 is a sectional view on the line 30 4-4 of Fig. 2.

Figure 5 is a detail view of the cross bar upon which the table is mounted, showing the manner of constructing the same in telescoping sections.

Figure 6 is a detail view of the rest which may be adjustably applied to the table to support a book when the table is in inclined position.

Corresponding and like parts are referred 40 to in the following description and indicated on all of the views of the drawings by like reference characters.

The base of the device is in the form of a frame which is adapted to rest upon the 45 seat of a chair and comprises the two side bars 1 which are pivotally connected at their rear ends by the links 2. These links are pivotally connected to each other and to the side bars 1 and can be adjusted to 50 admit of the side bars being held the desired distance apart. When the device is in position the side bars extend along opposite sides of the chair seat, and the forward ends of the side bars are provided with up- 55 rights or standards 3. The uprights are

preferably extensible so that the length thereof can be varied and in the present instance each of the uprights comprises a lower section 3^a and an upper section 3^b. The ends of these sections overlap each other and have a pin and slot connection 4 so that they are maintained in alignment with each other, although the upper section can be moved up and down to adjust the height of the upright. A set screw 5 is provided for clamping the two sections 3^a and 3^b of the upright in an adjusted position.

The upper ends of the uprights are connected by a transverse bar 6 upon which the 70 table 7 is mounted. The bar 6 is extensible, being formed in sections which overlap and have a pin and slot connection 6^a, whereby the two sections are held in alignment with each other although they can be moved in 75 and out to lengthen or shorten the bar. The extremities of the transverse bar 6 are extended downwardly at 6^b and provided with bolts 8 which are adapted to be received in notches or slots 9 in the upper ends of the uprights 3. Thumb nuts 8^a are threaded upon the bolts 8, and it will be obvious that when these thumb nuts are tightened the cross bar can be securely fastened to the upper ends of the uprights 3, although when the thumb nuts are loosened the cross bar and table can be readily lifted out of position.

The table 7 may be formed of any suitable material, although in the present instance it is constructed of sheet metal and provided at the sides thereof with depending flanges 10 which are formed with openings 11 to receive the bar 6. The bar is preferably flat in formation so that it cooperates with the openings 11 to hold the table in a fixed position upon the bar, although the bar and table can be tilted into any desired angular position when the thumb nuts 8^a are loosened.

The table is shown as comprising end strips 7^a and a plurality of intermediate strips 7^b which may or may not be spaced from the end strips and from each other, as may be desired. At the upper and lower edges of the table the strips 7^a and 7^b are connected by cross pieces 12 which have the ends thereof turned downwardly at 12^a. The strips 7^a and 7^b are secured to the cross pieces 12 by small bolts 13 or similar fastening members which are preferably detach- 105 110

able so that the table can be taken apart and packed in a small amount of space for shipment or storage.

When using the device the base which comprises the side bars 1 and links 2 is placed upon the seat of a chair and the side bars 1 adjusted the desired distance apart. The uprights 3 can then be properly arranged and clamped in an erect position by means of the set screws 14 which are provided at the pivotal connection between the lower ends of the uprights and the side bars. The length of the uprights can be adjusted to bring the table the desired height in front of the occupant of the chair. After the occupant has seated himself in the chair the bolts 8 at the ends of the cross bars 6 are brought into position in the slots 9 at the upper ends of the uprights and the thumb nuts 8^a then tightened while the table is held at the desired angular position. The table then provides a convenient support for magazines, newspapers or the like, and the device is held firmly in position by reason of the fact that the occupant of the chair is seated upon the links 2. When the occupant wishes to get out of the chair the thumb nuts 8^a are loosened so that the table can be easily lifted out of position.

The device can be easily adjusted to fit different sizes of chairs and the table can be held at the elevation and angle which may be particularly desired by the occupant of the chair. When the device is not in use it can be collapsed and packed in a small amount of space.

The intermediate strips 7^b of the table may be formed at their adjacent edges with a series of corresponding notches 15 and any selected pair of these notches is adapted to be engaged by the arms of a U-shaped clip 16 which may be formed of spring wire. The arms of the clip can be flexed inwardly toward each other to disengage them from the notches preparatory to removing the clip from the table or shifting it into engagement with another pair of the notches. The arms of the clip terminate in laterally extended portions 16^a which engage the bottom of the table when the clip is in position, the clip itself projecting through the opening so that it will form a rest for a book or magazine when the table is tilted into an inclined position.

Having thus described my invention what I claim as new and desire to secure by Letters Patent is,

1. A device of the character described, including spaced side bars adapted to rest loosely upon a chair seat, pivoted links connecting the side bars adjacent their free ends so that they can be moved toward and away from each other, said links fitting flat against the chair seat and being adapted to receive the weight of the occupant of the

chair, a table, and means upon the side bars for detachably supporting the table.

2. A device of the character described, including side bars adapted to be arranged upon opposite sides of the occupant of a chair, adjustable means connecting the side bars and extending across the chair seat and fitting flat thereon so as to receive the weight of the occupant of the chair, uprights carried by the side bars and comprising vertically adjustable members, and a table supported by the uprights for rotative adjustment thereon. 75

3. A device of the character described, comprising side bars adapted to rest upon a chair seat, link members pivotally connecting the side bars so that the latter can be moved toward and away from each other, said link members extending across the chair seat so as to receive the weight of the occupant of the chair, uprights pivotally connected to the side bars, means for clamping the uprights in adjusted position, and a table detachably carried by the uprights. 80 85

4. A device of the character described, comprising side bars adapted to rest loosely upon a chair seat, links adjustably connecting the side bars and extending across the chair seat so as to receive the weight of the occupant of the chair, uprights projecting from the side bars and adjustable thereon toward and from the seat, a cross bar connecting the uprights and pivotally connected thereto, and a table carried by the cross bar and adapted to be swung by movements thereof into different angular positions. 90 95 100

5. A device of the character described, comprising side bars adapted to rest loosely upon a chair seat, links adjustably connecting the side bars, said links extending across the chair seat so as to receive the weight of the occupant of the chair, uprights projecting from the side bars and having slotted ends, a cross bar connecting the uprights, clamping bolts carried by the ends of the cross bar and received removably within the slots of the uprights, and a table mounted upon the cross bar. 105 110

6. A device of the character described, comprising a supporting frame adapted to rest loosely on a chair seat and having portions adapted to receive the weight of the occupant of the chair, spaced uprights projecting therefrom, a cross bar connecting the uprights and having a detachable connection therewith for rotative adjustment, and a table supported on the cross bar and having slotted flanges through which the cross bar passes to interlock therewith to hold the table in position thereon. 115 120 125

7. A device of the character described, comprising a supporting frame adapted to rest loosely upon a chair seat and having a portion fitting flat upon the seat and adapted to receive the weight of the occupant of 130

the chair, spaced pivoted uprights projecting therefrom and having slotted upper ends, a flat cross bar connecting the uprights, clamping bolts carried by the ends of the cross bar and pivotally mounted within the slots of the uprights for adjustably and removably clamping the cross bar to the uprights, and a table mounted upon the cross bar and having flanges provided with openings receiving and interlocking with the sides of the flat cross bar to hold the table in position thereon.

8. A device of the character described, in-

cluding a pair of side bars adapted to be arranged upon opposite sides of the occupant of a chair, means connecting the side bars adjacent their free ends and extending across the chair seat so as to receive the weight of the occupant of the chair, uprights pivotally connected to the side bars, means for holding at said pivots the uprights in an adjusted position, and a table supported by the uprights for rotative adjustment thereon.

In testimony whereof I affix my signature.

FLOYD D. JONES.
